DESIGN FOR SUSPENDERS

Fred R. Culver, Wilson, N. Y.

Application November 12, 1938, Serial No. 81,059

Term of patent 14 years

To all whom it may concern:

Be it known that I, Fred R. Culver, a citizen of the United States, residing at Wilson, in the county of Niagara and State of New York, have invented a new, original, and ornamental Design for Suspenders, of which the following is a specification, reference being had to the accompanying drawing, forming part thereof.

The figure is a perspective view from the rear of suspenders, showing my new design.

I claim:

The ornamental design for suspenders, as shown.

FRED R. CULVER.
